(57) CLAIM

The ornamental design for a webcam clip, as shown and described.

DESCRIPTION

FIG. 1 is a perspective view of a webcam clip showing my new design;

FIG. 2 is a front elevational view thereof;

FIG. 3 is a rear elevational view thereof;

FIG. 4 is a left side elevation view thereof;

FIG. 5 is a right side elevation view thereof;

FIG. 6 is a top plan view thereof;

FIG. 7 is a bottom view thereof;

FIG. 8 is a perspective view thereof attached to a webcam;

FIG. 9 is a perspective view thereof attached to a webcam in an alternate position of use; and,

FIG. 10 is a perspective view thereof at a reduced scale attached to a webcam and a laptop computer.

The broken line showing of a webcam, USB cable, and laptop computer in FIGS. 8-10 is for illustrative purposes only and forms no part of the claimed design.
